HAND GRIP FOR SCREWDRIVERS OR THE LIKE

Lawrence H. Taylor, Holmdel, N.J., assignor to Republic Industrial Corporation, New York, N.Y., a corporation of Delaware

Application April 14, 1959, Serial No. 55,510

Term of patent 14 years

(Cl. D93—4)

FIG. 1

FIG. 2

FIG. 3

Fig. 1 is a side elevational view of a hand grip for screwdrivers or the like showing my new design with the tool in position and in broken lines for illustrative purposes only;

Fig. 2 is an elevational view taken from the right of Fig. 1; and,

Fig. 3 is a top plan view thereof.

I claim:

The ornamental design for a hand grip for screwdrivers or the like, as shown and described.
